CLAIM

The ornamental design for a locking member of horizontal supporter for scaffolds, as shown and described.

DESCRIPTION

FIG. 1 is an isometric view of a locking member of a horizontal supporter for scaffolds showing my new design. FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof; and,

FIG. 7 is a bottom plan view thereof.

1 Claim, 7 Drawing Sheets
